INVENTOR

Edwin P. Benson,

BY
Frank J. Leut
ATTORNEY

UNITED STATES PATENT OFFICE.

EDWIN P. BENSON, OF NEW YORK, N. Y.

PRINTING DEVICE.

Application filed October 10, 1922. Serial No. 593,523.

To all whom it may concern:

Be it known that I, EDWIN P. BENSON, a citizen of the United States, residing at New York, in the county of New York and State of New York, have invented certain new and useful Improvements in Printing Devices, of which the following is a specification.

This invention relates to printing devices, and more particularly to devices adapted to be assembled within a chase. These devices or units are assembled within a chase for the purpose of printing various blanks such as checks, insurance policies, etc. The units may include various cuts or engravings, ordinary type, display type, and various other printed matter which makes up the desired sheet. These units are assembled within the chase and are held in place by devices such as quoins or wedges. It has frequently been found, especially where one of the units is a device such as a numbering machine adapted to be actuated to number the sheets in succession during the printing operation, that the process of justification, i. e. the adjustment of the printing characters to a given line or position, is difficult. This difficulty arises initially since it is frequently necessary to move the device through indefinite fractions of the printer's scale units. It is still more difficult to adjust it after the chase has been fully set, since this necessitates loosening all the units within the chase. It is one object of this invention to provide a holder for a device such as a numbering machine wherein the printing characters may be easily adjusted at will to any desired degree.

It is a further object of this invention to provide a holder of the type described wherein the adjustment of the printing characters may be made without disturbing any of the other units in the printing chase.

Other objects and aims of the invention more or less broad than those stated above, together with the advantages inherent, will be in part obvious and in part specifically referred to in the course of the following description of the elements, combinations, arrangements of parts, and application of principles constituting the invention; and the scope of protection contemplated will appear from the claims.

In the accompanying drawings, which are

to be taken as part of this specification, and in which I have shown merely a preferred embodiment of this invention,

Fig. 1 is a bottom plan view of a device embodying my invention.

Fig. 2 is a section taken on the line 2—2 of Fig. 1.

Fig. 3 is a vertical section taken on the line 3—3 of Fig. 1.

Fig. 4 is a perspective detail showing a side guide-bar.

Fig. 5 is a perspective detail showing one of the end members of the movable frame.

Referring to the drawings, there is shown a frame 10 comprising side members 11 and end members 12. Within said frame is adapted to be mounted some form of printing or character-bearing device. The frame 10 and the characters supported thereby form a unit adapted to be inserted within the frame of the usual chase together with a plurality of other units such as cuts, engravings, etc. All of these units are held within the chase by wedges or quoins.

It frequently happens in printing blanks such as checks, insurance policies, etc., that a numbering machine is embodied in one unit and is actuated repeatedly during the printing operation to number the blanks successively. These numbers must be positioned accurately on a given line or at a given point. In the present invention the numbering machine is mounted within the frame 10 of the unit and is movable therein, so that at no time is it necessary to loosen all the units within the chase in order to align the numbering device, as was hitherto necessary. The unit comprising the numbering device is locked in the chase and all adjustments of the printing characters of said device may be performed without disturbing the other units of the chase.

The numbering machine is shown at 15 suitably mounted in a support comprising end-rails or bars 16. Said bars are provided with tenons 17 at their ends slidably in grooves 18 formed in the side bars 11 of the frame 10. A groove 19 is formed beyond each groove 18 and communicating therewith for the purpose of lubrication. The end bars 16 are provided with studs 20 doweled therein, or cast integrally therewith, and extending toward the end members 12 of frame 10. Adjusting nuts 22 are

threaded upon studs 20, and expansile core springs are interposed as shown between end bars 16 and end members 12.

By screwing said nuts tightly against the respective members 12, the sliding frame supporting the numbering device will be locked in position on the frame 10 when fixed in the chase.

For the justification of the printing line 10 of the numbering device it is only necessary to loosen that nut 22 which is in the direction toward which the line is to be moved and correspondingly tighten the other nut; the springs 21 meanwhile acting as balancers 15 relative to the slidable frame. Thus in Fig. 1, if the device is to be moved toward the bottom of the sheet, the lower nut is loosened (i. e. moved upwardly) while the upper nut is tightened (i. e. moved upwardly), causing 20 the numbering device to slide downwardly in grooves 18. The operation of these locking nuts in the process of justification will be readily apparent.

The numbering device may be of any 25 standard type, as shown adapted to be actuated in the printing operation by the reciprocation of a plunger 25. The side members 11 of frame 10 may be provided with scales 26 divided into standard printer's 30 scale units, with which cooperates an index 27 on the frame supporting the numbering machine.

Each nut 22 may be provided with apertures 30 in its periphery adapted to receive 35 a bar or rod 31 to facilitate turning of said nuts.

The above description illustrates the principles embodied in my invention but it will be understood that various changes and

modifications may be made within the scope 40 of the invention as defined by the annexed claims. Also, while I have illustrated the invention in connection with the printing line of a numbering machine, it will be understood that said invention applies to 45 any printing characters of a printing unit.

I claim:

1. In combination, a unit adapted to be mounted in a chase, said unit comprising a frame, a numbering machine slidably mounted in said frame, said machine including a member adapted to be actuated during printing to operate said machine, and means 50 coactive with the ends of the unit and the ends of the numbering machine for moving said machine relative to said frame.

2. In combination, a unit adapted to be mounted in a chase, said unit comprising a frame, a frame member having printing characters and slidably mounted in said frame, and means for moving said member relative to said frame, said means comprising 60 studs fixed to said member one at each end lock nuts carried by said studs and adapted to engage said frame.

3. In combination, a unit adapted to be mounted in a chase, said unit comprising a frame, a member having printing characters and slidably mounted in said frame, and means for moving said member relative to 70 said frame, said means comprising studs fixed to said member one at each end, nuts on said studs engaging the frame, and balancer springs between the member and frame.

In testimony whereof I affix my signature.

EDWIN P. BENSON.
